United States Patent Office.

THOMAS CARR LONGTON, OF TRENTON, NEW JERSEY.

Letters Patent No. 75,937, dated March 24, 1868.

IMPROVEMENT IN OIL-CUPS.

The Schedule referred to in these Letters Patent and making part of the same.

TO ALL WHOM IT MAY CONCERN:

Be it known that I, THOMAS CARR LONGTON, of Trenton, in the county of Mercer, in the State of New Jersey, have invented certain new and useful Improvements in Oil-Cans; and I do hereby declare that the following is a full and exact description thereof, reference being had to the accompanying drawings, and to the letters of reference marked thereon.

Figure 1 represents a longitudinal bisection, showing the inside view of a can.

Figure 2 represents the manner in which the nozzle is pressed down for the purpose of filling the can with oil.

Figure 3 represents a perspective view.

My invention consists in providing an oil-can with a movable nozzle, constructed with a spherical joint at the lower end, so that the can may be readily filled by simply depressing the nozzle, and pouring the oil into the cup.

To enable others skilled in the art to make use of my invention, I will proceed to describe the same. Similar letters of reference, where they occur, denote like parts in all the drawings.

Letter A represents the movable nozzle, the lower end of which passes through spherical knob B. Letter C represents a cup, which may be attached to the top of the can permanently, or by means of a screw, at the bottom of which the spherical knob B closely fits, forming a globe-joint. Letter D represents a spiral spring, which may or may not be fastened to the bottom of the spherical knob B, and the lower end of the spring fits into the socket a: This spring constantly keeps the spherical knob B in its proper position in the joint; also serves to force out the bottom of the can, thus forming the spring in the bottom necessary to force the oil from the nozzle.

An oil-can constructed in this manner can be easily filled by simply depressing the nozzle, and pouring the oil into cup C, which passes through the globe-joint, as shown in fig. 2.

The globe-joint can be made by making the bottom of the cup convex; or by using the spherical knob, over which a small piece of leather is placed. The latter is more preferable for convenience of manufacture. By this arrangement, the nozzle may be moved in any desired direction, the advantage of which is in oiling those parts of machinery which require the use of one curved or bent. This nozzle is much less liable to be broken or injured by a fall or other accident than those secured to the can in the ordinary manner.

Having thus fully described my invention, what I claim as new, and desire to secure by Letters Patent, is—

The oil-cup, with an adjustable nozzle, having a spiral spring beneath it, all substantially as shown and described.
